TOOL FOR APPLYING SEAL CAPS

John W. Shera, Chicago, Ill., assignor to American Flange & Manufacturing Co. Inc., Chicago, Ill., a corporation of Illinois

Application December 4, 1933, Serial No. 700,800

8 Claims. (Cl. 113—18)

My invention relates to a sealing tool and it has to do especially with a tool for applying seal caps to closure structure. My invention is well suited, for example, for the securement of a seal cap over the outer beaded end of a flange which defines an opening in the wall of a container.

One of the objects of my invention is to provide an improved tool of the foregoing character.

Another object is to provide an improved tool which is adapted to grippingly engage the side wall or skirt of a seal cap and move the same inwardly against the beaded end of the flange in such a manner that radial movement of the tool causes axial movement of the cap and the cap is depressed upon the closure structure and its side wall or skirt is uniformly contracted against the flange behind the beaded end without distortion of the closure structure or container wall.

A further object is to provide an adjustable tool of the foregoing character which is so arranged that predetermined adjustment will be maintained and torsional, and other, strains and stresses imposed thereon and movement of the tool parts upon the closure structure will not cause change in the adjusted condition of the tool, whereby each successive cap may be applied in substantially the same effective manner.

A more specific object is to provide a tool having a supporting body or stem member which rotatably supports means for centering the tool upon the cap and means for grippingly engaging and contracting the cap side wall or skirt upon and behind the beaded end of the flange, and which also adjustably supports handle structure and means actuated thereby for operating said gripping means.

Additional objects are to provide positive stop means determining the limits of movement of tool operating handle structure; to provide novel means for positively locking the handling operating structure in predetermined adjusted position upon the supporting body member; and to provide a strong and durable tool embodying the foregoing features and which may be manufactured cheaply and may be easily and quickly repaired.

Other objects and advantages will become apparent as this description progresses and by reference to the drawings wherein,—

Figure 1 is an elevational view of one form of tool embodying my invention;

Fig. 2 is an assembly view of the central supporting body or stem member and the parts for mounting the handle operating structure thereon, the several parts being shown in perspective;

Fig. 3 is an assembly view (the parts being shown in perspective) of parts of the jaw unit;

Fig. 4 is an enlarged vertical sectional view of the structure shown in Fig. 1, the tool being shown in position ready for securement of a cap;

Fig. 5 is a section taken substantially on line 5—5 of Fig. 4;

Fig. 6 is a view similar to Fig. 4 except looking in the opposite direction and showing the tool in the position it may assume after the seal cap has been applied;

Fig. 7 is a section taken substantially on line 1—1 of Fig. 6; and

Fig. 8 is an enlarged fragmental sectional view showing the condition of the tool parts, the seal cap and other parts of the closure structure in the final sealing position of the tool.

The tool shown in the drawings is well adapted for applying seal caps to the filling and/or discharge openings of metallic containers used, for example, in the storing and shipping of gasoline, oil, and the like, products.

Referring to Figs. 4, 6 and 8, the container wall 10 is formed of comparatively thin material and it is provided with an opening surrounded by an outwardly-extending flange 11 in which there is mounted, in seal-tight fashion, an internally threaded bushing 12 having its outer end turned over and upon the outer end of the flange 11 to form a bead 13. A plug (not shown) is usually screwed into the bushing to primarily close and seal the opening. To further seal the opening and to prevent undetectable tampering with the closure, a seal cap 14 is mounted over the plug and beaded end 13. It is highly desirable that the seal cap 14 be applied without such pressure in axial direction as would tend to distort the container wall 10 and disturb the sealed relation between the bushing 12, flange 11 and other parts of the closure structure. My invention provides an improved tool for applying the seal cap 14 in the manner stated.

Specifically, the tool which I have chosen to illustrate my invention includes a central supporting body or stem member 15, a jaw unit 16, a centering head or member 17, handles 18 and a bell-shaped jaw-operating member 19.

The jaw unit 16 includes a spider member having a hub 21 rotatably mounted upon the lower end of the supporting stem member 15. A plurality of annularly arranged jaw members 22 are pivotally mounted upon pins 32 between the arms 23 of the spider, and the upper ends of the jaw members are provided with extensions 24 which are embraced by a spring ring 25 which yieldably

swings the lower ends of the jaw members 22 outwardly and holds them in the open or expanded condition shown in Fig. 4. Each jaw member is of general wedge shape in outline and they have 5 arcuate outer surfaces so that the jaw unit in its contracted or closed condition is of bell-like shape. The lower ends of the jaw members 22 are provided with inwardly extending jaw elements 26 which have jaw faces 26^a adapted to 10 grippingly engage the side wall 27 of the cap as the jaw unit is moved toward its contracted position of Fig. 6. The number and shape of the jaw members 22 are such that, when they are fully contracted, their jaw faces form a true and complete circle (Fig. 7).

The lower end of the stem member 15 is provided with an enlarged head 28 and, between this head and the hub 21 of the jaw spider, there is 15 rotatably mounted the inverted cup-shaped centering member 17 which is of such diameter that its lower edge or rim is adapted to seat upon the peripheral edge of the cap 14 when the tool is applied thereto (Fig. 4). The member 17 together with the jaw elements 26 serve to position and 20 center the tool upon the cap for proper engagement of the latter by the jaw elements 26. The jaw spider and member 17 are rotatable upon and 25 relative to each other and they are held against axial displacement along the stem member 15 by 30 a spring ring 30 mounted in a suitably-provided groove 31 in the stem member 15.

In the maintenance and upkeep of the tool, it is 35 desirable to lubricate, from time to time, the pivotal support for the jaw member 22. To this end, passages 33 are provided in the hub portions of the jaws leading to the pins 32. For access to the passages 33, the member 17 is provided with an opening 34 in one side thereof and, upon inverting the tool and rotating the member 17 to 40 align its opening 34 with the passage 33 in the jaw members 22, a lubricant may be applied to such passage in an obvious manner.

The jaw members 22 are contracted by downward movement of the bell-shaped member 19 45 which encloses such jaws and has its lower inner surface shaped complementally to the outer surface of the jaw members 22. The jaw members are expanded by the spring ring 25 when the member 19 is raised to release the same. The 50 jaw-operating member 19 is actuated by a pair of handles 18 in the manner which will now be described.

The upper end of the supporting stem 15 is threaded, as at 35, and a handle-supporting 55 spider 36 is adjustably mounted thereupon. This spider includes an internally-threaded hub portion 37 which is adapted to be screwed upon the threaded end of the stem, and it is also provided with diametrically opposed, spaced pairs of arms 60 38 between which the inner ends of the handles 18 are pivotally mounted upon pins 39. Each handle, below and slightly offset outwardly from the pins 39, is provided with an ear 40 to the opposite sides of which there are pairs of links 42 65 and 42^a pivotally connected by pins 41. The other ends of the links of each pair are pivotally connected by pins 43 to diametrically opposed arms 44 on the top of the jaw-operating member 19. In the use of the foregoing arrangement, upward movement of the handles 18 raises the member 19 to permit expansion of the jaw members 22 and lowering of such handles moves the member 19 downwardly along the outer surfaces of the jaws to contract the latter as shown in Fig. 6.

The raising and lowering movements of the

handles 18 are limited in the following manner: The handle ears 40 are extended inwardly toward the stem member 15 to provide shoulders 45 which, when the handle is lowered to the position of Fig. 6, abut the under side of the handle 5 spider hub 37. Further downward movement of the handle, and further contracting or closing movement of the jaws 22 is thereby prevented. To limit the other movement of the handle, one of the links 42^a is provided with a centrally-disposed projection 46 extending inwardly toward the stem member 15 and it is so positioned and shaped that, as the desired upper limit of movement of the handles is reached, it seats against the under side of the adjacent handle supporting 15 spider arm 38.

In the assembly of the several parts of the tool, they should be so related that, when the handles 18 are moved to their lower limit, the jaw members 22 will be contracted and closed to their 20 complete circle condition shown in Fig. 7. The adjustable connection between the handle supporting spider 36 and the upper end of the stem member 15 permits of relative adjustment between the jaw-operating member 19 and jaws 22 25 to accomplish this result, notwithstanding the usual allowances for variation in size and fitting in the manufacture of the several parts of the tool. That is, by adjusting the handle supporting spider 36 inwardly or outwardly along the 30 stem member 15, the jaws can be made to close to greater or lesser extent.

In the proper operation of the tool, it is essential that, once the proper jaw closing adjustment be effected, it be maintained. To that end, 35 I positively lock the handle supporting spider 36 to the stem member 15. Specifically, I employ a lock washer 47 (Figs. 1 and 2) having a plurality (preferably, but not necessarily, four) of arms 48 arranged in diametrically opposed pairs. The 40 inner edge of this washer 37 is also provided with an inward projection 49 which, when the washer is placed over the outer end of the stem member 15 and upon the top of the handle spider 36, enters a longitudinal groove 50 in the stem preventing 45 relative rotation of the washer. When the washer is thus applied, a lock nut 51 (which has a plurality of flat surfaces upon its outer part) is screwed upon the outer end of the stem member 15 and tightly against the washer 47. One 50 of the diametrically opposed pairs of washer arms 48 is then turned upwardly against the adjacent flat sides of the nut 51 and the other washer arms 48 are turned downwardly between the handle 55 spider arms 38, thereby positively locking the handle spider 36 against rotation relative to the stem member 15. The washer arms 48 which engage the lock nut prevent rotation of the latter so that spider 36 is fixed against axial displacement movement.

The general operating relationship between the foregoing tool structure, the cap 14 and bead 13 is similar to that disclosed in the co-pending application of Fleck W. Sample, Serial No. 573,695 filed November 7, 1931. The seal cap 14 with a 60 ring-type gasket 52 is mounted over the bead 13 with the gasket seated upon the top of the bead, as shown in Fig. 8, and with the skirt of the cap extending freely down over the bead as shown in Fig. 4. In this position of the tool, the centering 65 member 17 is seated upon the top of the cap and the jaw elements 26 assume a position wherein, when they are moved radially inward, their work engaging faces 26^a will grippingly engage the cap skirt near its free edge. This engagement is at a 70 75

substantially uniform depth around the entire circumference of the cap skirt.

When the tool is actuated to contract the jaw-members 22, the cap side wall is first grippingly engaged by the work-engaging faces 26^a of the jaw elements. As the handles 18 are moved apart, the cap skirt is moved inwardly against the bead 13 slightly below the diameter of the latter; this relationship being determined by the fixed position between the lower or cap-engaging edge of the centering member 17 and the work-engaging faces 26^a of the jaw elements. As the contracting action of the tool is continued, and the jaw members 22 move radially inward, the gripped cap side wall is moved along the curved surface of bead 13, thereby pulling down or depressing the cap 14 substantially to the position shown in Fig. 6 with the lower edge of the cap side wall uniformly contracted into close, snug fit engagement with the outer surface of the flange 12. During this operation, the centering member 17 does not apply any substantial downward pressure to the top of the cap, any pressure effect of such member being merely incidental to the weight of the tool and the pressure exerted by the operator in moving the handles 18 in certain working positions in which the tool may be used. In the foregoing operation, the relationship of the parts is such that in cooperation with the bead 13, the radial movement of the tool is translated into axial movement. As the result, the sealing pressure applied through the tool is not sufficient to distort the container wall and it does not affect the sealed relationship between the bushing 12 and flange 11.

It will be appreciated that, in the foregoing operation, the tool is necessarily subjected to torsional, and other, strains and stresses. The jaw members 22 close in circumferential direction when they are simultaneously contracted, and there is a slight twisting action as they gradually and uniformly contract the skirt of the cap. There also may be a tendency for the operator in bringing the handles downwardly to tend to apply slight twisting action to the tool as a whole. It has been found in practice that, under these conditions, with the jaw unit 16 and the centering member 17 rigidly fixed to the stem or body member 15 considerable pressure is applied to the member 15 tending to disturb the fixed connection between it and the handle spider 36. Under some conditions, the strain and pressure applied to the stem member 15 through the jaw unit 16 and the centering member 17 may be such as to even shear or otherwise disturb a positive lock arrangement such as that afforded by the lock washer 47. However, I completely avoid these strains and stresses upon the stem member, and thereby further positively insure maintenance of the fixed relation between the handle operating spider 36 and the member 15, by rotatably mounting the jaw unit 16 and the centering member 17 upon the stem member 15 as hereinabove described. Any twisting movement or any tendency to apply twisting strains and stresses to the stem member 15 through these parts, as above stated, is entirely eliminated.

With the foregoing arrangement, the length of life of the tool is materially increased. Wear of the parts is materially reduced. The tool will perform its intended work uniformly, without attention, even in the hands of unskilled workmen, over long periods of time. In the event of wear of the cap-engaging surfaces 26^a of the jaw elements 26, or of the slide-engaging surface be-

tween the bell-shaped member 19 and the jaw members 22, the lock between the handle supporting spider 36 and the stem member 15 may be released and the spider 36 adjusted so as to cause the jaws to close to the desired extent.

It will be understood that while I have shown and described only one form of structure embodying my invention, other changes in details and arrangement of parts may be made without departing from the spirit and scope of my invention as defined by the claims which follow.

I claim:

1. In a tool for applying seal caps, a body member, tool centering means rotatably mounted on said body and fixed against longitudinal displacement, cap skirt contracting means rotatably mounted on said body and fixed against longitudinal displacement, reciprocable means for actuating said contracting means, and means for operating said reciprocable means which includes a member adjustably fixed to said body, handle means supported by said adjustable member, and connections between said reciprocable means, said handle means and said body member for reciprocating said reciprocable means within definite limits.

2. In a tool for applying seal caps, a body member, tool centering means rotatably mounted on the lower end of said body and having a part adapted to seat upon the peripheral edge of the cap top, cap skirt contracting means rotatably mounted on said body above said centering means and having a cap skirt engaging part surrounding and extending beneath said centering means, means for preventing axial movement of both said centering and contracting means, reciprocable means surrounding said cap skirt contracting means for actuating said contracting means, and means for operating said reciprocable means which includes a member adjustably fixed to said body at its end opposite said centering means, handle means supported by said latter member, link connections between said reciprocable means and said handle means, and means for limiting the extent of reciprocation of said reciprocable member.

3. In a tool for applying seal caps, a central supporting member, a tool centering member adapted to seat upon the cap and rotatably mounted on said supporting member, a jaw unit rotatably mounted upon said supporting member and centering member and including a plurality of expandable and contractible members adapted to engage the side wall of the cap, means locking both said centering member and jaw unit against axial displacement to maintain a fixed axial relationship therebetween, means for expanding and contracting said jaw unit, and means for operating said first means which includes a member immovably carried by said supporting member, handle members carried by said immovable member, operating connections between said handle members and said expanding and contracting means, and means for limiting expansion and contraction movements of said expandable and contractible members.

4. In a tool for applying seal caps and having a supporting body, tool centering means on said body, and cap skirt contracting means on said body; means for operating said contracting means which includes a reciprocable member engageable with said contracting means, a handle-support member on said body, a lock nut on said body primarily securing said handle-support member thereto, a handle supported by said han-

idle-support member, a connection between said handle and said reciprocable member, means for limiting movement of said handle to limit reciprocatory movement of said reciprocable member to predetermined extent, and means interengaged with and for positively locking said handle-support member to said body against movement in any direction to prevent variation in limits of reciprocation of said reciprocable member, said latter means being capable of release for adjustment of said handle-support member to vary the positions of the limits of reciprocation of said reciprocable member.

5. In a tool for applying seal caps, a supporting body, means engageable with the cap skirt for contracting the latter, and means for operating said skirt contracting means which includes a reciprocable member engageable with said contracting means, a member immovably mounted 10 on said body above said contracting means, handles pivotally supported by said immovable member, link members connecting said handles and said reciprocable member, said handles being movable away from each other and toward each 15 other to reciprocate said reciprocable member, and a stop element on one of said link members engageable with said immovable member as said handles are moved together to limit the extent 20 of such movement.

6. In a tool for applying seal caps, a supporting body, means engageable with the cap skirt for contracting the latter, and means for operating said skirt contracting means which includes a reciprocable member engageable with said contracting means, a member immovably mounted 25 on said body above said contracting means, handles pivotally supported by said immovable member, link members connecting said handles and said reciprocable member, said handles being movable away from each other and toward each 30 other to reciprocate said reciprocable member, stop elements on said handles engageable with said immovable member as said handles are

5 moved apart to limit the extent of such movement, and a stop element on one of said link members engageable with said immovable member as said handles are moved together to limit the extent of such movement.

7. In a tool for applying seal caps, a supporting body, a jaw unit carried by said body and having a plurality of jaw members contractible to engage and secure the cap skirt, a member reciprocable upon said jaw unit for expansion and contraction of said jaw members, and means for reciprocating said reciprocable member which includes a member immovably carried by said body, handles movable in opposite directions to reciprocate said reciprocable member, link members 15 connecting said handles and said reciprocable member, a stop element on at least one of said handles engageable with said immovable member for limiting downward reciprocation of said reciprocable member and extent of contraction of 20 said jaw members, a stop element on one of said link members for limiting upward reciprocation of said reciprocable member, and an adjustable connection between said body and immovable member for varying the position of the lower limit 25 of reciprocation of said reciprocable member to vary the extent of contraction of said jaw members.

8. In a tool of the class described a supporting body, a jaw unit including a spider member 30 mounted on said body, pins carried by said spider member, jaw members having hubs rotatably supported on said pins, said hubs having lubricating passages therein leading from the inner surfaces thereof to said pins, an inverted cup-shaped 35 centering member rotatably mounted on said body and enclosed by said jaw members whereby said centering member normally obstructs access to said passages, said centering member having an opening in one side thereof so that by 40 rotating the same access may be had to said passages through said opening.

JOHN W. SHERA.
